(57) **CLAIM**

We claim the ornamental design for a holder for portable telephone, as shown.

DESCRIPTION

FIG. 1 is a top, front, and right side perspective view of our new design for a holder for portable telephone;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a top front, and right side perspective view of our new design showing its use with a portable phone that forms no part of the invention;

FIG. 9 is a rear elevation view thereof with a front portion at an angle to a rear portion; and,

FIG. 10 is a rear elevation view thereof with a front portion in a horizontal position with respect to a rear portion.
